UNITED STATES PATENT OFFICE.

JOHN J. HARRIS, OF NEW YORK, N. Y.

REPLY-CARD ADVERTISING BLOTTER.

Application filed April 19, 1919. Serial No. 291,403.

To all whom it may concern:

Be it known that I, JOHN J. HARRIS, a citizen of the United States, residing at New York, in the county of New York and State 5 of New York, have invented certain new and useful Improvements in Reply-Card Advertising Blotters, of which the following is a specification.

This invention relates to a means for advertising, and has for its object to provide an inexpensive device which will be sufficiently valued for considerations of utility to insure its retention by the recipient; which will, when in use, present to view and 10 enforce upon the user's attention, an advertising message, proposal for business, or overture for correspondence; and which will be accompanied by a readily available mailing card upon which the recipient may conveniently indicate his wishes with reference 15 to the subject-matter of the advertisement, and which card will be carried by the advertising device in a manner to make its presence manifest when the advertising device is received or when put into use, and therefore the more effective or suggestive 20 as regards the purpose of the advertisement.

Accordingly, the invention consists in providing an advertising device in the form of 25 what I shall term a reply card advertising blotter, embodying in its construction a sheet-like body of absorbent material having its under side available as a blotting surface and having upon its side that is 30 opposite thereto, and which is presented to view when the blotter is in use, a surface bearing advertising matter, and having between said body of absorbent material and the advertising surface thus provided a 35 pocket containing a mailing or order card 40 for use in replying to the advertisement, said card being carried in the pocket in such manner that the fact of its presence is appreciated by the user, and its examination 45 and use for the purpose intended rendered the more likely to occur.

In the accompanying drawing—

Figures 1, 2, 3, and 4 show one illustrative embodiment of the invention; Figure 1 50 being a face view of the advertising device complete; Figure 2 a longitudinal section

thereof; and Figures 3 and 4 the obverse and reverse, respectively, of the return mailing card carried thereby.

In all the figures, 1 represents a blotter 55 having an under plate-like sheet 2 of absorbent material, and an upper ply, sheet, or layer 3 of material suitable to have advertising matter imprinted thereon.

Formed between the absorbent plate 2 and the ply, sheet, or layer 3, as, for instance, by adhering the latter to the former along three sides and leaving them free and separable throughout an appropriate portion of their area, is a pocket 4 extending inwardly 65 from one end of the blotter but terminating sufficiently short of the opposite end and having its sides sufficiently spaced from the longitudinal edges of the body sheet to leave adhering areas of the top sheet that develop 70 substantial marginal portions; and this pocket contains a return mailing card substantially fitting the pocket and raising the wall thereof, which is provided by the top sheet, sufficiently above the adhering areas 75 of the top sheet to develop not only at one end but along the sides of the pocket a distinct drop in surface which serves as an indicator appreciable to the sense of touch and thereby rendering the presence of the return 80 card manifest when the blotter is used, thus causing the card to serve as a forcible suggestion to the user of the blotter, and thereby rendering the device more effective than if the pocket extended over the whole of the 85 surface and did not fit the card in a manner to develop a sharp demarcation between the two levels of the rubbing surface of the blotter.

I claim:

A reply card advertising blotter, embodying in its construction a substantial body sheet of absorbent material providing an under surface exposed for use as a blotter, and having upon its upper surface a continuous 90 top sheet bearing advertising matter; the meeting faces of said body sheet and top sheet being adhered together except over a reduced area thereof extending inward from one edge of the body sheet to provide a 95 pocket; and an order card located in said pocket, closely fitting the same, and raising 100

above the general surface of the top sheet
the wall of the pocket provided by said top
sheet: the area of adhesion forming a well
defined marginal surface on three sides of
5 said pocket in a distinctly lower plane than
said wall of the pocket, and thereby provid-
ing with said pocket an indicator of the

presence of the order card in the pocket, ap-
preciable by the sense of touch while using
the blotter.

Signed at New York, New York, this 11th
day of April, 1919.

JOHN J. HARRIS.
